UNITED STATES PATENT OFFICE.

WILLIAM WESTLAKE, OF MILWAUKEE, WISCONSIN.

IMPROVEMENT IN LANTERN-GUARDS.

Specification forming part of Letters Patent No. 42,520, dated April 26, 1864.

To all whom it may concern:

Be it known that I, WM. WESTLAKE, of the city of Milwaukee, in the State of Wisconsin, have invented a certain new and useful Improvement on Lantern Guards; and I do hereby declare that the following is a full, clear, and exact description thereof, reference being had to the accompanying drawings, and to the letters and marks thereon.

In many instances it is desirable that the guard of the lantern should be removed, and hence a detachable guard is valuable; but it is important that such detachable guard, when on the lantern, should be well secured, not liable to be loosened by accident, and not presenting hooked or irregular points and surfaces against which other objects would come in contact, or on which a part of one's dress or other articles would be caught. A guard that has to be unhooked or disjointed in order to be removed is, therefore, objectionable. My invention looks to the attaching and detaching of the guard as a whole, or as one piece—securely held when on the lantern, easily and readily removed therefrom or attached thereto, and having no hooks, or projections, or catches sticking out and interfering with the safe and convenient use of the lantern.

The drawings forming part of this specification show by Figure 1 a lantern with my guard affixed thereon or thereto, and by Fig. 2, a transverse sectional view of the upper part of the guard and lantern, as taken at the red line of Fig. 1, and as seen from a view looking upward. The guard *a* is made of the usual

material, and so securely made up that it becomes but one piece. The upper ring or annular bar *b* has a flange looking inward, *c*, onto which, when the guard is fully fitted on the lantern *d*, catches *e* rest and hold the guard in place. These catches *e* are on the end of flat springs *f*, which are secured to the inner surface of the cap-piece *g*, knobs *h* having stems which pass through holes in the cap-piece *g*, and are attached to the catch end of the springs *f*, allow of the removal of the catches *e* from the surface of the flange of the ring or bar *b*. The thumb and finger of one hand of the lantern-carrier can easily operate the knobs and catches. When thus loosened, the removal of the bottom of the lantern—the oil-cup part—allows of the removal of the guard and of the ready attachment of the guard by simply putting it around the lantern and pressing it upward. As is evident, other catches and means for securing the guard to the lantern may be used in the place of those here described.

What I claim as my invention, and desire to secure by Letters Patent, is—

Attaching the lantern-guard to the lantern so that as a whole, and without any hinging or separating of its parts, it may readily and speedily be removed from the lantern, substantially as herein set forth.

WM. WESTLAKE.
